UNITED STATES PATENT OFFICE

2,642,003

BLOWER INTAKE PORT

Joseph E. Whitfield, Erie, Pa., assignor to Read Standard Corporation, a corporation of Delaware

Application December 16, 1949, Serial No. 133,295

2 Claims. (Cl. 103—128)

1

This invention relates generally to fluid pumps, motors, blowers, compressors and similar devices of the type employing rotary engaging members provided with helical intermeshing threads, and more particularly to the housing which encloses and cooperates with the rotary members to produce a fluid device having definite operating characteristics.

Fluid devices of the type described have a pair of rotatably mounted rotors provided with complementary intermeshing helical threads and grooves preferably of such configuration to provide a continuous seal line therebetween and which cooperate with the walls of the chambers in which they rotate to form fluid pockets that advance from one end of the chambers to the other. When operating as a motor the fluid pressure on the faces of the rotary members propels them, and when operating as a pump, blower or compressor the fluid is propelled by the rotation of the intermeshing rotors.

The male rotor, referred to as the main rotor, has preferably all or full addendum threads with the pitch circle being substantially at the root diameter. The female rotor, referred to as the gate rotor, has its complementary threads all or full dedendum with the pitch circle being substantially at its outside diameter. These complementary intermeshing helical threads form a continuous seal with each other since the curved sides of the helical main rotor threads are generated or described by the continuous crest edges of the helical threads of the gate rotor, and the curved troughs of the gate rotor are generated or described by the continuous crest edges of the helical threads of the main rotor. These rotary members are shown and described in my United States Patent No. 2,287,716, granted June 23, 1942.

The intermeshing rotary members operate in parallel cylindrical chambers which merge into one another, forming a larger chamber, somewhat in the form of a figure 8 in cross section. Theoretically, the rotary members form a continuous seal with each other and their peripheral surfaces seal with the walls of their respective chambers. Actually it is desirable that they have a running clearance to prevent actual contact, and this clearance depends on the size of the apparatus. However, the clearance is so small that an effective seal is provided. This spaced relation of the rotors is maintained by timing gears although they are capable of driving one another.

The ports are located at diagonal corners of the housing or casing and extend over a portion of the ends and sides of the two chambers to

provide both axial and radial communication with the rotary members. If the ports are the same size and shape at each end, the direction of rotation of the rotary members determines which is the inlet and which is the outlet. In the present invention, one of the ports and its passage is particularly designed to serve as the intake, and the rotary members are therefore rotated in a direction so that the pockets formed by the rotors together with their chamber walls advance from this intake end of the chambers to the other or outlet end of the chambers.

The present invention has as its primary object, the provision of a device of the type described having improved performance through an improved fluid intake port and port passage construction particularly adapted to facilitate flow of fluid into the pockets formed by rotation of the rotors.

20 In devices of the type described, wherein the fluid intake provides for radial admission of fluid to the rotors, it has been found that the rotor threads, during that part of their rotation which is outwardly toward the intake, have a tendency to reverse the fluid flow and throw it out of the intake passage, thus impeding entrance of fluid to the rotor pockets during rotation of the rotor threads. It is an object of the invention to provide an improved intake passage construction that overcomes this objection and that, furthermore, does not interfere with axial admission of fluid where the intake port is formed for axial as well as radial admission of fluid to the rotors.

Another object of the invention is to provide an improved intake passage for facilitating radial admission of fluid to the rotor pockets. At the high speed of rotation of the rotor members, it is apparent that they are in communication with the fluid intake for a comparatively short time, and in order to obtain highest efficiency from the device a full volume of fluid must be delivered to the rotor pockets.

In my improved construction the fluid entering the intake passage is divided substantially into two streams, one stream being directed toward the main rotor chamber and the other stream being directed toward the gate rotor chamber, the air being so directed that it is flowing in the same direction that the periphery of the rotor is moving.

The invention further contemplates an improved intake passage construction wherein said passage gradually tapers and decreases in size, or cross section, from the inlet port to the end of the passage where said passage merges with the

end wall and sides of the casing. Thus the momentum of the incoming air tends to force the air into the more confined space formed as the rotor threads approach the casing wall.

Other objects and advantages of the invention will become apparent from the following description when read in connection with the accompanying drawings, in which

Figure 1 is a longitudinal, vertical sectional view taken through the axes of the rotary members of the device, with parts shown in elevation;

Figure 2 is a side elevation of the device with the rotor members removed showing the novel fluid intake construction, with parts broken away to show the outlet port;

Figure 3 is a sectional view taken on the line 3—3 of Figure 2 with the rotors removed;

Figure 4 is a sectional view taken on the line 4—4 of Figure 2 with the rotors shown in section;

Figure 5 is a sectional view taken on the line 5—5 of Figure 2 with rotors removed;

Figure 6 is a sectional view taken on the irregular line 6—6 of Figure 3;

Figure 7 is a sectional view taken on the irregular line 7—7 of Figure 3;

Figure 8 is a sectional view taken on the line 8—8 of Figure 2;

Figure 9 is a sectional view taken on the line 9—9 of Figure 2;

Figure 10 is a sectional view taken on the line 10—10 of Figure 3; and

Figure 11 is a sectional view taken on the line 11—11 of Figure 2.

Referring now to the drawings, particularly to Figure 1, the blower includes a housing 10 transversely split into the two housing sections 11 and 12. The housing sections 11 and 12 are rigidly secured together by suitable means, as by the bolts 13, shown in Figure 5, that extend through the mating peripheral flanges 14 and 15. The housing 10 encloses a pair of parallel cylindrical chambers 16 and 17 which intersect to form a large common chamber, the cross section of which is substantially in the form of a figure 8.

Mounted for rotation in the housing 10 are a pair of meshing helical rotors, a female or gate rotor 18 in the chamber 16 and a male or main rotor 19 in the chamber 17. The main rotor 19 preferably has two threads while the gate rotor 18 preferably has four, making the ratio one to two. The threads of the main rotor extend through substantially 180° while the threads of the gate rotor extend through substantially 90°. A minimum practical clearance is provided between the peripheral envelope of the rotors and the wall of the housing 10. The profiles of the rotors 18 and 19 may be made in accordance with the disclosure in my United States Patent No. 2,287,716, granted June 23, 1942; wherein the crest edges of the main rotor threads generate the adjacent sides of the gate rotor grooves and the crest edges of the gate rotor threads generate the curved sides of the main rotor threads.

The gate rotor 18 is mounted for rotation in the bearing and bearing carrier assemblies 20 and 21, received respectively in a sleeve 22 preferably integrally formed with end wall 23 of housing section 11 and a sleeve 24 preferably integrally formed with and extending between inner and outer end walls 25 and 26 of housing section 12. The main rotor 19 is mounted for rotation in the bearing and bearing carrier assemblies 27 and 28, received respectively in a sleeve 29 preferably integrally formed with end wall 23 of housing sec-

tion 11 and a sleeve 30 preferably integrally formed with and extending between inner and outer end walls 25 and 26 of housing section 12. A minimum practical clearance is provided between the end faces of the rotors 18 and 19 and the housing end walls 23 and 25.

Timing gears 31 and 32 are mounted on the shafts of the gate rotor 18 and the main rotor 19, respectively, for synchronizing the operation of the rotors. The drive (not shown) for the rotors is connected to the extended shaft portion 33 of the main rotor 19 on that side opposite the timing gear 32.

The housing section 11 is provided, at its end 15 adjacent the end wall 23 and on one side of a plane intersecting the axes of the rotors 18 and 19, with a discharge passage 34 having an outlet opening 9 and terminating at its inner end in a discharge port 35 formed by relieving adjacent portions of the end wall 23 and side wall of housing section 11, as best shown in Figure 2.

The housing section 12 is provided, at its end adjacent the end wall 25 and on the opposite side of a plane intersecting the axes of the rotors 18 and 19, with an inlet passage 36 having an inlet opening 8 and terminating at its inner end in an inlet port 37 formed by relieving adjacent portions of the end wall 25 and side wall of housing section 12. The peripheral extent of the end wall 25 is, as best shown in Figure 3, defined by the line connecting points marked a, b, c, d, e, f, g, and that portion of end wall 25 defined by the line a, b, c, d, e, f, g, forms an edge of the port 37.

Now, by looking particularly at Figures 1 and 3 it will be seen that, the space between the edge of the port 37 defined by the line a, b, c, d, e, f, g, and the peripheral envelope of the rotors 18 and 19, forms with the outer end wall 26, the side wall of housing section 12 and the outside wall 40 of the sleeves 24 and 30, a chamber 38 that is substantially in the shape of a figure 3 and that provides for axial admission of fluid to the working spaces or pockets bounded by the threads of the rotors 18 and 19 as the pockets pass the port edge a, b, c, d, e, f, g, during rotation of rotors 18 and 19.

As best shown in Figures 3, 6 and 7, the chamber 38 constitutes part of the inlet passage 36 and the arrows A and B in Figures 6 and 7, respectively, show the direction of the fluid through the passage 36 axially into the rotor pockets. The terminal portions of the 3-shaped chamber 38 are, as best shown in Figures 1, 6 and 7, closed by sloping wall portions 39 and 40 joining the inner and outer end walls 25 and 26. The sloping wall portions 39 and 40 prevent the formation of eddy currents and provide for a free and continuous flow of fluid into the ends of the rotor pockets.

In order to further direct the fluid into the ends of the rotor pockets a sloping wall portion 41 is provided that joins the inner and outer end walls 25 and 26 and extends from the edge of the wall 26 adjacent the inlet opening 8 of passage 36 inwardly towards the ends of the rotors 18 and 19 to the peripheral edge of the wall 25, as best shown in Figures 3, 8, 9 and 11.

The portion of port 37 providing for radial admission of fluid to the rotor pockets is, as stated before, formed by relieving portions of the side wall of the housing section 12. Referring particularly to Figure 10 the letters v, w and x, y, z indicate the longitudinal extent of the relieved portion of the side wall of housing 12 and represent edges of port 37.

The peripheral extent of the relieved portions of the side wall of housing 12 are best shown in Figures 3 and 4 and extend from g to n and from o to a , and represent the peripheral extent of the port 37. The relieved portions of the side wall of housing 12 included between g , n and o , a and extending back from the inner end wall 25 to v and x , y , z therefore constitute the portion of port 37 that provides for radial admission of fluid to the rotor pockets.

Walls 42 and 43 of the inlet passage 36 extend in a generally tangential direction from the periphery of the rotors 18 and 19 from the port edges g and a and then curve inwardly toward each other to the inlet opening 8, as best illustrated in Figures 3 and 4, to form in the passage 36 chambers 44 and 45 radially disposed with respect to the rotors 18 and 19. The chambers 44 and 45 are in communication with the axially disposed chamber 38, previously described, whereby fluid entering the passage 36 is delivered both radially and axially through inlet port 37 to the rotor pockets.

Referring again to Figures 3 and 4, it is evident that the portion of chamber 44 included between wall 42 and the peripheral envelope of rotor 18 tapers toward port edge a or in other words in the direction of fluid flow to the pockets of rotor 18, and that portion of chamber 45 included between wall 43 and the peripheral envelope of rotor 19 tapers toward port edge g or in other words in the direction of fluid flow to the pockets of rotor 19.

The design of the intake port as set forth above is important in supplying the rotor pockets with a full volume of fluid. Because of the high speed of rotation of the rotors a centrifugal force is created that normally tends to throw the incoming fluid out of the rotor pockets. However, as the rotor 18 rotates from the position shown in Figure 4 in the direction of the arrow, the rotor pocket that is shown communicating with the intake port of passage 36 remains filled since the fluid tending to escape because of the centrifugal action is confined by the wall 42 that forms with the peripheral envelope of the rotor, a chamber of progressively decreasing cross sectional area.

The wall portions 46 and 47 of passage 36, as best shown in Figures 2, 5, 8 and 9 slope from the inner marginal edge of walls 42 and 43, respectively, inwardly to the periphery of the rotors 18 and 19. These sloping walls 46 and 47 together with the wall portions 51 and 52 bound chambers 48 and 49, as best shown in Figure 5, which form continuations, respectively, of the chambers 44 and 45. By sloping the wall portions 46 and 47, it is apparent that a greater peripheral area of the rotors is opened up to admit fluid to the rotor pockets, and at the same time, these wall portions 46 and 47 guide the fluid into the rotor pockets.

Disposed centrally of the passage 36 and extending longitudinally from the passage walls 46 and 47 to the plane of the housing inner end wall 25, is a wedge shaped deflector member 53. The diverging faces 54 and 55 of the deflector meet in a ridge 56 adjacent the inlet opening 8 of the passage 36, and slope, respectively, toward the walls 42 and 43 of the passage 36 as they extend inwardly thereof. The deflector 53 is preferably integrally formed with the side wall of the housing section 12 and as can best be seen in the sectional views 3, 4 and 5, the wall 57 of the deflector 53 opposite the ridge 56 fits

closely the contour of the rotors 18 and 19 with a minimum practical clearance and forms a part of the housing side wall.

The edge defining the junction of the wall 57 and the sloping wall 54 of deflector 53 lies approximately in the horizontal plane passing through the axis of gate rotor 18, while the edge defining the junction of the wall 57 and the sloping wall 55 of deflector 53 lies approximately in the horizontal plane passing through the axis of main rotor 19.

It will be seen, referring particularly to Figure 4, that the deflector 53 directs the fluid through the passage 36 into the chambers 44 and 45 in the direction of rotation of the rotors 18 and 19, the direction of rotation being indicated by the arrows. Rotating in the direction shown, the leading faces of the rotor threads as they emerge from beneath the wall 57 of deflector 53 and travel inwardly away from the inlet opening 8 of the passage 36, they sweep the fluid into the rotor pockets, assuring a full volume of fluid for subsequent delivery to the discharge passage 34.

Again referring to Figure 4, it will be seen that the deflector 53 prevents the leading faces of the rotor threads, as they travel outwardly toward the inlet opening 8 of the passage 36, from throwing the fluid out of the passage 36. In other words, without the deflector 53, a portion of the fluid entering the passage 36 would be thrown out, and would prevent a full volume of fluid from entering the rotor pockets, resulting in lowered capacity and efficiency.

It will be observed, referring particularly to Figure 4, that as a new pocket forms due to rotation of the rotors, this pocket is covered radially by the wall 57 of the deflector 53 but is open axially for admission of air between the outer end of the deflector 53 and the wall 41 as shown in Figure 2. When the rotor threads emerge from under the wall 57, a rotor thread of each of the rotors 18 and 19 being shown in emerging position in Figure 4, the rotor pockets are opened for radial as well as axial admission of air.

The porting arrangement as shown in the drawings provides a device of the compressor type, since the rotor pockets are sealed against communication with both the inlet and outlet ports 37 and 35 for a period of time during rotation of the rotors 18 and 19, in which time the rotor pockets will be reduced in volume as the meshing of the rotor threads advance toward the discharge end of the device. In other words, opening of the pockets to the outlet port 35 is delayed for a time after the rotor pockets are sealed from the inlet port 37, and the duration of delay determines the degree of compression of the fluid within the pocket before it is discharged.

It will be obvious, that the device can readily be converted to eliminate compression of the fluid by extending one or both ports 35 and 37, so that delay in communication between the ports is eliminated, and the invention is of course equally applicable to a device of this type.

I claim:

1. In a fluid device of the character described, a housing structure including side walls and end walls defining a pair of parallel cylindrical chambers to form a common chamber, adapted to receive intermeshing spiral lobed and grooved rotors cooperating with each other and the housing structure to form fluid pockets that progress 70 from one end of the housing to the other during

rotation of said rotors, intake and outlet ports in opposite end portions of said housing, said intake port having portions thereof in both said side and end walls to expose portions of the ends and peripheral envelopes of said rotors, an intake passage provided with wall portions registering with the edges of said housing side and end walls defining said intake port, said intake passage walls extending in a laterally outward direction with respect to the plane common to the axes of said rotors, to provide for admission of fluid therethrough in a radial direction to said rotors, the peripheral extent of the port in said housing side wall being such as to expose the greater portion of the peripheral envelope of the intermeshed rotors, and the wall portions of said intake passage that register with the longitudinally extending port edges in said housing side wall sloping progressively away from the peripheral envelope of the intermeshed rotors from the last named port edges toward the inlet end of said intake passage, to provide at the inner end of said intake passage between said sloping wall portions and the peripheral envelope of said intermeshed rotors a pair of branching tapered passages for radial admission of fluid to the rotor pockets in a generally tangential direction, the wall portion of said intake passage that registers with the port edges in said housing end wall being offset in an axial direc-

tion with respect to the ends of said intermeshed rotors, and a deflector in said intake passage having a pair of diverging sides disposed respectively to direct radially admitted fluid to said respective branching tapered passages, said deflector being wholly in that portion of said passage radially outward of said intermeshed rotors.

2. Apparatus according to claim 1 in which the deflector is disposed wholly between planes 10 passing through the axes of the rotors and which planes are normal to the plane common to the axes of the rotors.

JOSEPH E. WHITFIELD.
